(57) **CLAIM**

The ornamental design for a cigar knife, as shown and described.

DESCRIPTION

FIG. 1 is a front perspective view of a cigar knife showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion indicated by line 9 in FIG. 1.

The evenly-spaced broken lines in the drawings depict portions of the cigar knife that form no part of the claimed design.

The broken lines consisting of long-short-dash lines are for purposes of annotating the enlarged view only and form no part of the claimed design.
